CLEANING COMPOSITION

Elizabeth P. MacDonald and Naomi W. Stenglein,
Saginaw, Mich.No Drawing. Application January 17, 1936,
Serial No. 59,552

6 Claims. (Cl. 87—5)

This invention relates to a material for use in the cleaning of painted, varnished or other like surfaces, the principal object being the provision of material of the type described which will permit such surfaces to be cleaned thoroughly and rapidly without affecting the finish thereof and which may be so employed as to leave a protecting covering on the surface cleaned, and is a continuation in part of our Letters Patent 10 of the United States No. 2,032,372, issued March 3, 1936 for Method of cleaning and coating surfaces.

Objects of the invention include the provision of a material which may be dissolved in water and employed to clean painted, varnished and other surfaces in a quick and efficient manner without adversely affecting the finish thereof; the provision of a material as above described which, when a small amount of a solution thereof is allowed to remain and dry upon the surface cleaned thereby, will leave a protecting film upon such surface; the provision of a material as above described in which such film allowed to remain and dry upon a surface cleaned by the material will act to protect the surface against foreign material thereafter deposited upon it and which film is soluble so as to thereafter enhance the ease with which subsequently deposited foreign material may be removed from such surface.

Other objects of the invention include the provision of a cleaning mixture or compound including glue and a cleaning agent, the weight of the glue constituting 25% to 50% of the total weight of the mixture; the provision of a cleaning mixture including glue and one or more elements of 35 a class including borax, sodium carbonate, and trisodium phosphate, the glue constituting approximately one-third of the total weight of the mixture; the provision of a cleaning mixture including glue, sodium carbonate and trisodium phosphate, the glue constituting 25% to 50% of the entire weight of the mixture and the sodium carbonate or borax, and trisodium phosphate being present in substantially equal amounts; and the provision of a cleaning compound including 45 glue, and anhydrous sodium carbonate, and trisodium phosphate, the glue and anhydrous sodium carbonate and trisodium phosphate being present in approximately equal amounts by weight.

50 The above being among the objects of the present invention, the same consists in a certain novel mixture of material to be hereinafter more fully described, and then claimed, having the above and other objects in view.

55 We have found that a water solution of glue,

where the glue is present in sufficient quantities, when applied to a surface has an exceptional tendency to draw any water soluble or loose foreign material which may be upon the surface into the solution and away from the surface. If, in treating the surface, an appreciable amount of such solution is allowed to remain on the surface and dry, the glue in the solution remaining on the surface and drying will form a protective film over the surface which, because of the character 10 of glue, imparts a gloss or luster to the surface and which, because of its transparency, has no discolored effect whatsoever. If foreign material should be again deposited upon the surface, the film of glue separates it from actual contact 15 with the surface and should the surface again be cleaned the film of glue is readily dissolved and removed, carrying with it the foreign material. This not only provides a quick and convenient way of both protecting and/or cleaning a surface 20 and by following out such procedure the character of the surface may be maintained free of the effects of foreign material for a relatively long period of time.

It is, of course, rather difficult for a water solution of glue by itself to remove foreign material from a surface that is not soluble in water and which adheres to the surface, and we have discovered that if an additional suitable element or elements are introduced into the solution, practically all foreign material which may be found upon a surface, may be quickly and readily removed with a minimum of physical exertion. The additional element or elements which are preferably employed with the water and glue for 35 this purpose may be borax, sodium carbonate, trisodium phosphate or equivalent materials and one or more of such elements may be employed in the broader aspects of the invention. We have discovered that in order to prevent such elements 40 from adversely affecting the surface by penetration thereof the glue should constitute three-eighths of one per cent to two per cent of the total solution, and should constitute 25% to 50% of the combined weight of the glue and the cleaning element or elements other than water. Although any one or more of the elements described may be used with the glue and water to form a suitable solution, we prefer to employ either sodium carbonate or borax, and preferably the 50 former, and trisodium phosphate for the reason that the sodium carbonate or borax acts to soften the water and the trisodium phosphate acts to penetrate the foreign material and permit its ready removal. Preferably the sodium carbonate 55

or borax and trisodium phosphate are present in approximately equal amounts and individually in amounts approximately equal to the glue.

In marketing the material it is, of course, preferable to mix the glue and one or more elements described in a dry state and allow the ultimate user to dissolve the required amount of the mixture in the required amount of water. In such case the mixture sold will comprise from 25% to 10 50% glue, bone glue being preferable because of economy although any other suitable type will function satisfactorily. The remainder of the mixture will, of course, constitute one or more of the elements borax, sodium carbonate, trisodium 15 phosphate or their equivalent and preferably trisodium phosphate with either sodium carbonate or borax. While the proportions of the elements other than the glue may be varied where two or more such elements are employed, we prefer to 20 employ sodium carbonate or borax in equal amounts with trisodium phosphate. Sodium carbonate is preferable particularly from the standpoint of cost. Also anhydrous sodium carbonate is preferably employed for the reason that its 25 water content is usually about 12%, while the water content of hydrous sodium carbonate is approximately 54% and where the mixture is formed with hydrous sodium carbonate, there is a tendency to cake which, although it does not 30 affect the ultimate result, makes it more difficult to dissolve the mixture in the water.

A preferred composition of material or mixture for the above described purposes includes approximately 36% glue, 32% anhydrous sodium 35 carbonate and 32% trisodium phosphate. Coloring matter or material designed to give a distinct scent or odor to the mixture may be added if desired, but inasmuch as such material is usually and preferably inert as far as the action of the 40 mixture is concerned, it may be considered as merely additive to the above stated proportions and, accordingly, is not taken into consideration in the following claims. It will also be apparent that other elements that may have certain desirable 45 results may be added to the above composition without affecting the broad invention herein.

Where such a dry mixture is prepared for marketing purposes it will, of course, be understood that the various elements entering into it are 50 preferably reduced to powdered or granular form and intimately inter-mixed with each other. In employing this mixture for the purposes of cleaning a surface, preferably two to five ounces of the mixture are dissolved in a gallon of water. A 55 cloth or other element is then immersed in the solution, partially wrung out and then employed to rub or wash the surface which it is desired to clean, the cloth being repeatedly rinsed in the solution as often as is required to maintain it 60 suitably free of the foreign material and, of course, as soon as the solution becomes sufficiently contaminated with the foreign material, it is dispensed with and replaced by some new solution. In cleaning a surface in the manner described, it is preferable not to wipe the surface dry 65 but rather to leave an appreciable amount of the solution on the surface and allow it to dry thereon. The solution in drying on a wall will leave a minute coating of glue over the surface and any foreign material which may thereafter become deposited on the surface will be separated 70 from actual contact therewith by the film of glue. Furthermore, this coating of glue will enhance the luster and gloss of the surface. Obviously, 75 should the surface thereafter be again cleaned,

the application of water to the film of glue will dissolve it and the foreign material will readily be removed therewith.

It may be noted that the material may be used as an initial protective covering for newly painted 5 or other surfaces, thereby permitting greater ease in subsequent cleaning operations and eliminating the possibility of the foreign material initially affecting the surface before it is cleaned with the preparation disclosed. 10

It is to be particularly noted that the cleaning agents disclosed herein, namely borax, sodium carbonate and trisodium phosphate, if alone or in combination with each other, are dissolved in water without the addition of glue and employed 15 to clean a surface, they will have an adverse effect upon the surface such as, for instance, attacking the paint where the surface is a painted surface, but we have discovered that where glue in sufficient amounts is employed with such a 20 cleaning agent, the glue prevents such agent from penetrating the surface sufficiently to effect the character thereof, and a minimum amount of glue which we have found capable of being employed to successfully resist the penetrating effect 25 particularly of the trisodium phosphate is approximately 25% of the dry mixture. We have also discovered that if less than 25% of the dry mixture disclosed comprises glue then there will be an insufficient amount of glue left on the surface 30 to provide the necessary film or coating to properly protect the surface from foreign material thereafter deposited upon it. Accordingly, it will be understood that the amount of glue should never be reduced below the minimum amount 35 stated if the objects of the present invention are to be adequately attained.

Likewise we have found that the addition of glue in amounts greater than 50% of the dry mixture is undesirable for the reason that not 40 only does it tone down or reduce the cleaning effect of the other element or elements to an undesirable extent, but additionally it is liable to leave too heavy a deposit of glue on the surface where the coating of the solution of the material allowed to remain on the surface and to be dried thereon is unusually heavy and unevenly distributed, for in such case visible streaks due to the variation in thickness of the glue film may often times be apparent. As above stated we 45 have found that when the glue constitutes approximately one-third of the dry mixture best all round results are obtainable.

While the mixture disclosed is particularly adaptable for use in connection with cleaning 55 painted, varnished or other like surfaces, we have also discovered that it is also admirably suitable for use in connection with cleaning carpets, rugs or the like as the sodium compound loosens the dirt or other foreign material in the 60 nap and the adhesive qualities of the glue draw the dirt or foreign material into the solution leaving the nap free from any soapy film. This is of considerable importance in protecting the life of a rug or carpet. In this connection it 65 may be pointed out that where rugs or carpets are cleaned with so-called soap, a film of the soap is invariably left on the carpet which acts to dull the color and luster thereof, while in using the herein described mixture the film which 70 is left enhances the color and luster of the nap as well as affords a protection therefor when an appreciable amount is allowed to dry thereon. It will, of course, be understood that in such case an appreciable amount will invariably remain on 75

the rug or carpet even though the same is apparently rubbed as dry as practical for, unlike painted surfaces, the nap of the rug or carpet will absorb a certain amount of the material from which the water will escape only by evaporation, thus leaving the required deposit of glue.

5 Formal changes may be made in the specific embodiment of the invention described without departing from the spirit or substance of the 10 broad invention, the scope of which is commensurate with the appended claims.

What we claim is:

1. A cleaning mixture to be thereafter dissolved in water for cleaning painted or varnished 15 surfaces consisting of 25% to 50% by weight of bone glue, and the balance consisting of a material selected from a class of substances consisting of borax, sodium carbonate and trisodium phosphate.
- 20 2. A cleaning mixture to be thereafter dissolved in water for cleaning painted or varnished surfaces consisting of 25% to 50% by weight of bone glue, and the balance consisting of a material selected from a class of substances consisting of borax, anhydrous sodium carbonate and trisodium phosphate.
- 25 3. A cleaning mixture to be thereafter dissolved in water for cleaning painted or varnished surfaces consisting of 25% to 50% by weight of bone glue, and the balance consisting of a material selected from a class of substances consisting of borax, sodium carbonate and trisodium phosphate.

solved in water for cleaning painted or varnished surfaces consisting of 25% to 50% by weight of bone glue, and the balance consisting of approximately equal parts by weight of trisodium phosphate, and a material selected from a class of substances consisting of sodium carbonate and borax.

4. A cleaning mixture to be thereafter dissolved in water for cleaning painted or varnished surfaces consisting of 25% to 50% by weight of 10 bone glue, and the balance consisting of approximately equal parts by weight of trisodium phosphate and sodium carbonate.

5. A cleaning mixture to be thereafter dissolved in water for cleaning painted or varnished 15 surfaces consisting of 25% to 50% by weight of bone glue, and the balance consisting of approximately equal parts by weight of trisodium phosphate and anhydrous sodium carbonate.

6. A cleaning mixture to be thereafter dissolved in water for cleaning painted or varnished surfaces consisting of approximately 33 1/3% by weight of bone glue, and the balance consisting of approximately equal parts by weight of trisodium phosphate and sodium carbonate.
